(57) **CLAIM**

The ornamental design for forward tilted faucet controls, as shown and described.

DESCRIPTION

FIG. 1 is a front perspective view of the forward tilted faucet controls according to my design, the brackets indicating that the precise spacing between the illustrated elements is not claimed;

FIG. 2 is a rear perspective view of the forward tilted faucet controls;

FIG. 3 is a front elevational view of the forward tilted faucet controls;

FIG. 4 is a top plan view of the forward tilted faucet controls;

FIG. 5 is a bottom plan view of the forward tilted faucet controls;

FIG. 6 is a left elevational view of the forward tilted faucet controls, the right side view being a mirror image thereof; and,

FIG. 7 is a rear elevational view of the forward tilted faucet controls.

The central faucet spout and mounting flanges are shown in broken lines for illustrative purposes only and form no part of the claimed design.
